No Drawing. Application June 6, 1941, Serial
 No. 396,926. In Great Britain June 21, 1940

2 Claims. (Cl. 167—20)

This invention relates to insecticides of the nature of sheep dips more particularly for the killing and eradication of insect pests and parasites from the skins of sheep and cattle and other domestic livestock, and while the invention is capable of general application as an insecticide it will, for convenience, be referred to herein generally by the term "dip."

Various forms of powder dip involving the use of finely divided sulphur are already known and, 10 in general, are very efficient.

It is also known to use solutions or emulsions of coal tar acid and oils in water and one example of this type of dip which has been in use for many years is a liquid mixture of low boiling cresylic acid and soap which on dilution with water forms a clear solution.

There have also been in general use for many years a number of paste dips comprising finely divided sulphur cresylic acid and soap and these combine the curative properties of both the sulphur and the cresylic dips while in addition we have found that the presence of the cresylic acid in the wash results in the retention of a greater amount of sulphur in the fleece near the skin of the sheep than would otherwise be possible and this effect enhances the value of the sulphur.

Such paste dips, however, are commonly diluted to give an efficient dipping bath with 50 to 70 times their weight of water whereas if the sulphur and cresylic acid present in the paste dips could be mixed together alone and added to water to prepare the bath they would dilute with 100 or more times their own weight of water to give a bath of the same concentration.

The object of the present invention is to devise a form of dip which will possess all the advantages of the hitherto known dips with other important advantages among which may be noted the following:

- (a) It is easy to pack and transport;
- (b) It is not affected by hard water;
- (c) It is easier to mix than is the plain sulphur dip; and
- (d) It will dilute with a high proportion of water to give an efficient bath containing a suspension of finely divided sulphur and a solution of cresylic acid.

It should here be noted that the term "cresylic acid" is used herein for convenience of description and is to be understood as including phenols and fractions of phenols extracted from coal tar and boiling between 185 and 350° C. and the substituted phenols, ethyl phenol and amyl phenol, 50 55

which may, or may not, occur in the same coal tar fractions.

The invention consists in an insecticide consisting of a powdered mixture comprising finely divided sulphur and a metal derivative of cresylic acid which, when suspended in water, hydrolyses irreversibly to give a solution of cresylic acid.

The invention further consists in an insecticide consisting of a powdered mixture comprising finely divided sulphur and aluminium cresylate.

In carrying our invention into effect in one convenient manner we prepare finely divided sulphur in any suitable manner and this we mix with powdered aluminium cresylate in suitable proportions to produce a powder dip which on addition to water is immediately suspended therein and within a short time hydrolyses to give a solution of cresylic acid; since the particles of the powder become evenly dispersed throughout the water before hydrolysis takes place there is no local concentration of cresylic acid which would tend to cause flocculation of the suspension of the finely divided sulphur.

25 The powder dip so produced is easy to mix, but, if desired, a wetting agent, e. g., tea seed cake may be added to increase the ease of mixing.

In preparing the sulphur it is preferred that this should be in as fine a state of division as possible, and should be substantially anhydrous.

In the preparation of the aluminium cresylate we may use aluminium or aluminium alloys in the form of scrap, turnings or other form but we prefer to employ the metal in the form of fine foil and to, say, 350 grams of scrap aluminium foil we add 50 grams of anhydrous cresylic acid with a small amount of aluminium cresylate (present in the vessel from a previous batch) and we heat these together in a suitable vessel. The reaction commences almost immediately when the source of heat may be removed and anhydrous cresylic acid is allowed to run slowly into the hot reacting mixture until, say, 3500 grams of acid in all have been used. By this method of procedure 35 the reaction may be kept under control and needs very little attention and when finally the whole of the cold acid has been added heat is applied and the mixture maintained at 230 to 240° C. until there is no further effervescence. The product while still hot and fluid is poured from the excess metal in the vessel (through a suitable filter) into a container and allowed to cool in the absence of air.

The aluminium cresylate is a translucent very brittle solid which is easily ground and sieved,

and the ground material when maintained alone or in admixture with finely divided sulphur in tightly stoppered bottles up to 37° C. shows no sign of caking even after long periods of time.

In addition to aluminium cresylate the following aluminium derivatives have been prepared in a similar manner and resembles aluminium cresylate in that they are solids capable of being easily ground and of being incorporated with finely divided sulphur in a powder dip, namely:

- (1) Aluminium phenate
- (2) Aluminium o-cresylate
- (3) Aluminium m-cresylate
- (4) Aluminium mixed cresylate (phenols in fraction 185-200° C.)
- (5) Aluminium mixed cresylate (phenols in fraction 200-210° C.)
- (6) Aluminium mixed cresylate (phenols in fraction 200-350° C.)
- (7) Aluminium guaiacolate
- (8) Aluminium xyleneate
- (9) Aluminium ethyl phenates (fraction of substituted phenols)
- (10) Aluminium amyl phenates (fraction of substituted phenols)

When using aluminium cresylate we find a suitable dip to consist of 47% aluminium cresylate, 41.5% dispersible sulphur powder and the balance wetting and dispersing agents, but it will be understood that the proportions used will depend upon the degree of concentration of the sulphur and cresyllic acid required in the bath.

It will be understood, however, that the invention extends broadly to a powder dip comprising finely divided sulphur and a hydrolysable metal derivative of cresyllic acid and it is therefore not to be limited to the details hereinbefore given by way of example as we may use any of the finely divided sulphurs already available on the market or may produce such finely divided sulphur in any suitable manner and may vary 10 the method of producing the cresyllic acid derivative depending upon the particular purpose to which the insecticide is to be applied, the conditions under which it is to be employed, or any practical requirements that may have to be met. 15 Moreover, in some cases it may be found desirable to add other powdered insecticidal agents such as derris or derris extract or arsenical compounds.

We claim:

1. An insecticide consisting of a powdered mixture comprising finely divided sulphur and an aluminium derivative of cresyllic acid which, when suspended in water, hydrolyses to give a solution of cresyllic acid.
2. An insecticide consisting of a powdered mixture of 47% aluminium cresylate, 41.5% dispersible sulphur powder and the balance wetting and dispersing agents.

EDWARD SYDNEY REDVERS WILLMORE.
FRANCIS ASHMOLE COOPER.
